CIRCUIT CONTROL MECHANISM

Weldon W. Betz, Culver City, Calif., assignor of
one-third to Cecil Betz Davis and one-third to
Byron H. Betz

Application April 20, 1938, Serial No. 203,072

2 Claims. (Cl. 200—97)

My invention relates to circuit control mechanism of the type which can be used for controlling the ringing of door chimes, flashers, and other apparatus where a series of interruptions in the flow of an electric current is desired, that is, to give an intermittent function.

Among the salient objects of my invention are:

To provide a mechanism of the character referred to wherein the closing of a switch, as by pressing a button, operates to set the mechanism to function intermittently, as where door chimes are struck three or four times in one operation;

To provide a mechanism of the character referred to wherein a fluid control operates to retard the return movement of the member which is set for operation by the closing of the switch;

To provide in combination with such a mechanism a series of contacts and a contact member adapted to be moved successively over said contacts in one direction, with means for returning said contact member free and clear of said series of contacts;

To provide in combination with a solenoid and plunger operating therethrough, a flexible or other valve member operating over the opening in the solenoid to open and close said opening as the plunger moves therein from the opposite end, to permit the outflow of the oil or other fluid in which said solenoid and plunger are submerged, while closing it against inflow as the plunger returns after being moved by the energizing of the solenoid;

To provide a simple, practical, economical and efficient control mechanism of the character referred to which can be used in many places where intermittent functioning of a circuit is used.

In order to explain my invention, I have illustrated one practical embodiment thereof on the accompanying sheet of drawings which I will now describe.

Figure 1 is a front view of a door chimes, with a part broken out to show my invention applied thereto;

Figure 2 is an enlarged plan view of my mechanism with the top removed or cut away;

Figure 3 is a vertical, longitudinal sectional view through Fig. 2, taken on line 3—3;

Figure 4 is a fragmentary sectional view taken on line 4—4 of Fig. 2; and

Figure 5 is a diagrammatic or wiring diagram.

Referring now in detail to the drawing, my invention can be applied to door chimes, such as shown in Fig. 1, in which the three chimes or tubes are designated 6, 7 and 8, and suspended to be struck successively in the usual manner, as by

means of electromagnets, as indicated in Fig. 5.

My invention as here shown applied to door chimes, consists of a box or case 9, closed and adapted to hold a fluid, as oil, in which the mechanism is submerged, said box having the supporting or connecting feet 10, 10, for securing it to the top of the chimes case or head, designated 11.

Mounted in said box 9 is a solenoid 12, having a tubular plunger 13, moving through the tubular member 12' of said magnet, which tubular member 12' is extended outwardly beyond the end of the coil, as indicated.

Around said plunger 13 is a coiled spring 14, the outer end of which is turned inwardly and inserted into said plunger, as at 15, while the other end of said spring is soldered or secured to tubular member 12', as at 16, Fig. 2, and is insulated therefrom.

Said spring 14 operates to withdraw or move said plunger 13 outwardly when the solenoid is deenergized.

Mounted in the outer end of said plunger 13, is a contact pin or finger 17, extended laterally over a block or member 18 of insulating material, such as rubber or Bakelite, supported on a bracket 19, on the bottom of the box 9, and held in place by a bolt 20. Set in said member 18, are four contact points, 21, 22, 23 and 24, having terminals 25, 26 and 27, for wires at 21', 22', 23' and 24', said wires being extended to and connected with three terminals, as 25, 26 and 27, the wire from contact point 24 is carried back to contact 21, as indicated in Figs. 2 and 5, for a purpose hereinafter again referred to. From the three terminals 25, 26 and 27, on the box, wires 25', 26' and 27' are extended to three solenoids, as 28, 29 and 30, indicated in the diagrammatic view, Fig. 5, which are in the door chimes housing 11, for striking the three tubular chimes, 6, 7 and 8.

The wires from the solenoid 12, are designated 31 and 32, Fig. 2, and connect with terminals 33 and 34 in the box 9, with wires 35 and 36 leading to a front door button or switch, designated 37, and thence to a transformer, designated 38, with another wire 39 leading to a rear door button or switch, designated 40, and thence connected at 42 with the wire 25' to chime solenoid 29, as seen in Fig. 5. The circuit wires from said solenoids 28, 29 and 30, designated 28', 29' and 30' are connected with a circuit wire 41, through a resistance 43, with the circuit wire 36, as seen in Fig. 5.

Mounted in the inside of the box 9, by means of a pivot bolt 44, is a movable lever 45, having at its free end an angle part 46, positioned so

that as the plunger 13, and the projecting contact pin 17 are withdrawn by the spring 14, said contact pin 17 is moved slowly over the contact points 21, 22, 23 and 24, in the member 18. The end of the spring 14, being inserted into the plunger, as at 15, tends to give a certain yielding tension to said plunger which operates to hold said contact pin 17 yieldingly down on the member 18.

When the solenoid 12 is energized, the plunger 13 is drawn thereinto, and the contact pin 17, instead of engaging the contact points 21, 22, 23 and 24, rides over them upon the angle lip or bridge 46, this movement being rather quick, but when the button is released and the solenoid 12 is deenergized, the plunger is moved slowly outwardly and the contact pin 17 successively engages said contact points, moving under and lifting said lever 45 sufficiently to pass thereunder.

An important feature of the invention is the fact that the mechanism within the box 9 is submerged in oil, or other suitable liquid. I have provided a flexible piece of leather 47, anchored at one end by means of a metal L-shaped member 49, bolted to the end of the box by a bolt 49, with the free end of said leather 47 arched over and resting against the open end of the tubular member 12' in the solenoid 12, whereby it acts as a valve over said end.

The plunger 13 fits the tubular member 12' of the solenoid 12 so as to permit leakage of the oil therebetween, so that when the solenoid 12 is energized and the plunger 13 is drawn into it, oil in said tubular member 12' is forced out past said flexible valve member 47, bulging it as indicated in light broken lines. The plunger 13 is closed at its outer end and would be filled with oil. As the plunger is moved to the right by the tension of the spring 14 thereon, the valve member 47 closes over the open end of the tubular member 12' and said plunger then must move slowly as the oil leaks into the solenoid between the plunger 13 and the tubular member 12'. This provides for a retarded movement of the plunger 13 and its contact pin 17 outwardly, said contact pin 17 moving over the contact points 21, 22, 23 and 24 and completing a separate circuit at each one and successively energizing the solenoids 29, 28 and 30 and thence back to 29, for successively striking the tubular chime members 7, 6, 8 and 7, as will be understood from the drawing and the circuit diagram in Fig. 5. It will be noted that contact points 23 and 24 are more closely spaced than points 21 and 22. This compensates for the retarded movement of the

contact pin owing to the fact that the spring 14 is nearly spent in its return resiliency.

It will be understood, of course, that any arrangement and spacing and even connections can be made to said contact points for the purpose of varying the type of sound given by the chimes, as may be desired.

It is believed that the circuits are clear and can be easily traced on Fig. 5. When either front or back door switch 37 or 40, are closed, the solenoid 12 is energized and the plunger 13 is drawn thereinto, the contact pin 17 riding above the contact points 21, 22, 23 and 24 on the ledge or angle part 46 of the lever 45. As the plunger moves outwardly again slowly, by reason of the oil leakage around the plunger, said plunger pin 17 contacts points 21, 22, 23 and 24, completing circuits which successively energizes the solenoids 29, 28, 30 and 29, striking chimes 7, 6, 8 and 7, as before referred to.

I claim:

1. In a circuit control mechanism, a liquid tight case, a plurality of fixed contacts therein with circuit connections thereto, a solenoid with a tubular center, a plunger operable in said solenoid and having a contact element thereon to successively move upon said fixed contacts to successively complete circuits, a spring for moving said plunger in one direction when the solenoid is deenergized, and a liquid of oil consistency in said case submerging said solenoid, plunger and fixed contacts, and a valve element operating to close the open end of said solenoid as said plunger moves outward, whereby to retard the movement of said solenoid and contact element over said fixed contacts.

2. A circuit control mechanism including a liquid tight case, a plurality of fixed contacts therein with circuits therefrom, a solenoid in said case having a tubular center open at both ends and extended at one end outside of said solenoid, a plunger moving in said tubular center and having a contact element on its end to move over said fixed contacts, a spring over said plunger and the extension of said extended tubular center for moving said plunger outwardly from said solenoid when the solenoid is deenergized, a flexible valve element over the open end of said tubular center for closing the same as said plunger moves out at the other end thereof, and a liquid in said case submerging said solenoid, plunger and contact element, said liquid operating to retard the movement of said plunger and said contact element over said fixed contacts when said solenoid is deenergized.

WELDON W. BETZ.
